UNITED STATES PATENT OFFICE

ANTON J. OBERG AND ROBERT R. STOEFEN, OF LOS ANGELES, CALIFORNIA

SPOTLIGHT PROJECTING MACHINE

Application filed February 29, 1928. Serial No. 258,065.

This invention relates to spotlights particularly useful, for theatrical purposes and the general object of the invention is to provide an improved spotlight projecting machine for producing spotlights of different designs in various colors, which machine may be readily and accurately adjusted to focus the light, and may be readily assembled or taken apart.

10 A more particular object is to provide a spotlight machine with improved ventilating means to prevent overheating thereof.

A further object is to provide a spotlight machine of the character stated which will be 15 simple in construction and highly efficient in operation.

The invention is illustrated in the annexed drawings which form a part of this specification and in which:

20 Figure 1 is a perspective view of my spotlight machine with the casing partly broken away to show the mechanism of the machine.

Figure 2 is a fragmentary cross-section of the casing as seen where broken away in the 25 right hand portion of Figure 1.

Figure 3 is a fragmentary rear view of the reflector and its adjusting means.

Corresponding parts are designated by the same reference characters in all the figures.

30 Our invention includes generally a casing 1, a slide holder 2, a reflector 3, a projecting light 4, a magnifying lens 5, a multicolored transparent wheel 6, a blower 7, and a motor 8.

35 The casing 1 is made in two sections, a lower section 9 and an upper section 10, the upper section being longitudinally slidably mounted on the lower section by means of slide joints 11 on the side upper and lower

40 edges of said lower and upper sections. The joints 11 are formed by bending the upper side edges of the lower section 9 first outwardly at 12, then upwardly at 13, then inwardly at 14, and then downwardly at 15, 45 and by bending the lower side edges of the upper section 10 first outwardly at 16 and then upwardly at 17. The bent portion 12 of lower section 9 forms a shoulder upon which slidably rests the lower edge portion 16 of upper section 10, while the portions 15 and 17

interengage to hold the upper section 10 in sliding relation on the lower section (see Figure 2). The upper edge of the forward end of the lower section 9 of the casing is formed with an external flange 18 while the lower edge of the forward end of the upper section 10 is formed with an inturned flange 19 which engages the under side of the flange 18 when the upper section is retracted on the lower section. A lens 20 is provided in the front end wall of the upper section 10 of the casing 9.

50 In the front end of the lower casing section 9 is secured a frame 21 formed with a base 22 and a pair of upstanding vertical members 23 and 24. A bar 25 which may be square in cross section is secured at its forward end to the frame member 24 while the rear end of said bar extends into a sleeve 26, in the

55 rear end of which sleeve is secured a screw block 27 with which a screw 28 engages which screw extends through and is journaled in the rear end wall of the lower casing member 9, there being a pair of washers 29 and 30 secured on said screw which washers engage the inner and outer sides of said rear end wall.

55 A thumb wheel 30' is secured on the rear outer end of the screw 28 for turning the same. The screw 28 and sleeve 26 support the rear end of the bar 25. On the

60 outer end of the screw block 27 is secured a bearing plate 31 formed with a plurality of bearings 32, 33, 24 and 25, through which extend adjusting rods 36, 37, 38 and 39 respectively for the slide holder 2, reflector 3, light 4 and magnifying lens 5.

65 The slide holder 2 is formed with a supporting member 40 and a sleeve 41 which slides on the sleeve 26, whereby the slide member is slidably mounted on the sleeve 26.

70 On the sleeve 41 is formed a lug 42 through which extends the inner threaded end 43 of the adjusting rod 36, said threaded end being in threaded engagement with said lug. The

75 slide holder 2 extends transversely of the upper section 10 of the casing 1 and is formed with plates 44 at its ends which cover at all times openings 45 in the side walls of said upper section, allowing for a short adjusting or focusing movement of the slide holder lon-

itudinally of the casing without escape-
ment of any light from the casing through
said openings. The rear end of the rod 36
extends through the rear end wall of the low-
er section 9 of the casing 1 and a knob 46 is
secured on the rear end of said rod. A pair
of washers 47 and 48 are secured on the rod
36 in engagement with opposite sides of the
plate 31 so that when the rod is turned one
way or the other the engagement of the screw
end 43 of said rod causes the slide holder 2
to be adjusted forwardly or backwardly. The
slide holder is provided with the usual light
openings 2a and 2b in its rear and front walls
respectively through which openings light is
projected by the light 4.

The reflector 3 is mounted on an arm 50
formed with a sleeve 51 which is slidably
mounted on the sleeve 26, the reflector being
formed at its rear with a stud 52 which pro-
jects through a vertical slot 53 in the arm 50
and is threaded to receive a nut 54, there be-
ing a washer 55 fitted on the stud against the
rear face of the arm against which washer
the nut 54 binds for adjustably securing the
reflector on the arm for vertical adjustment.
A lug 55 projects rearwardly from the up-
per edge of the reflector, through which lug a screw 56 extends which screw engages the
upper end of the arm 50, there being a shoul-
der 57 and a collar 58 on said screw engaging
the upper and lower sides respectively of the
lug 55 whereby, upon turning the screw 56
the reflector is adjusted vertically either up-
wardly or downwardly. The inner end of
the rod 37 is threaded at 59 for engaging the
arm 50 whereby said arm and the reflector 3
may be adjusted longitudinally of the casing
1 or towards or away from the light 4 and
slide 2. Washers 60 and 61 are secured on
the rod 37 adjacent opposite sides of the plate
31 for holding the rod against longitudinal
movement so that its screw may adjust the
arm 50 and reflector 3. A thumb wheel 62
is secured on the outer rear end of the rod
37 for turning the same.

The base 63 is secured on a sleeve 64 slid-
ably mounted on the sleeve 26 and a lug 65
depends from the sleeve 64 which lug is en-
gaged by the threaded end 66 of the rod 38.
A pair of washers 67 and 68 are secured on
the rod 38 adjacent opposite sides respec-
tively of the plate 31 so that upon turning the
rod the threaded end 66 engaging the lug 65
will cause the sleeve 64 and light 4 to be ad-
justed longitudinally of the casing 1 or to-
ward 3. A thumb wheel 69 is secured on
the outer rear end of the rod 38 for turning
the same.

60 The magnifying lens 5 is mounted on a
sleeve 70 which is slidably mounted on the
sleeve 26 and is formed with a lug 71 which
is in threaded engagement with the threaded
end 72 of rod 39. Collars 73 are secured on
the rod 39 in engagement with the plate 31 to

hold the rod against longitudinal movement
but to allow the rod to turn so that its
threaded end 72 engaging lug 71 will adjust
the sleeve 70 and lens 5 longitudinally to-
ward or away from the slide 2 and color wheel 70
6. A thumb wheel 74 is secured on the outer
rear end of the rod 39 for turning the rod.

The color wheel 6 is divided into a plurality
of sectors 75 of different colors. The wheel
is secured on a shaft 76 which is journaled
in bearings 77 and 78 on the upper ends of
members 23 and 24 respectively of frame 21.
A worm wheel 79 is secured on the color
wheel shaft 76 in mesh with a worm 80 on the
upper end of a vertical shaft 81 journaled in
bearings 82 and 83 on the frame member 24.
A worm wheel 84 is secured on the lower end
of shaft 81 in mesh with a worm 85 on the
shaft 86 of motor 8.

The inlet 87 of the blower 7 extends from
the atmosphere through the bottom wall of
the lower section of the casing 1 and the upper
section 10 of the casing is constructed with a
ventilator 88 in the top thereof so that air
drawn into the casing through said inlet after
circulating through the casing may escape
through said ventilator.

The operation of my invention is as fol-
lows: The slide holder 2 reflector 3, light 4,
and lens 5 being properly adjusted, a slide 90
of figured or lettered glass is introduced from
one side of the casing through an opening 45
into the slide holder 2. The light 4 being
lighted and the motor 8 put in operation, air
is circulated by the blower 7 through the cas-
ing and the color wheel 6 rotated by the motor
through the medium of motor shaft 86, worm
85, worm gear 84, shaft 81, worm 80, worm
gear 79 and shaft 76. The design of the slide
90 is projected by the light of light 4, re-
flected by reflector 3 through the openings 2a
and 2b of the slide holder 2 through the mag-
nifying lens 5, color wheel 6 and lens 20 and
the rotation of the wheel 6 bringing the dif-
ferent colored sectors 75 thereof successively
100 across the projected light produces a novel
varigated spotlight projected through the
lens 20.

We claim as our invention :

A spotlight projecting machine comprising
a front lense, a condenser lense spaced rear-
wardly of said front lense, a translucent color
element positioned between said lens, said ele-
ment having differently colored areas pro-
gressively movable across the field of vision,
115 an image-forming translucent member spaced
rearwardly of said condensing lense, and a
source of light located rearwardly of said
member to project light therethrough.

In testimony whereof we affix our signa-
tures.

ANTON J. OBERG.
ROBERT R. STOEFEN.
